UNITED STATES PATENT OFFICE

151,556

DESIGN FOR A SAVINGS BANK

Andrew Quackenbush, Clifton, N. J.

Application January 10, 1947, Serial No. 136,030

Term of patent 3½ years

(Cl. D34—11)

To all whom it may concern:

Be it known that I, Andrew Quackenbush, a citizen of the United States residing in the city of Clifton, in the county of Passaic and the State of New Jersey, have invented a new, original, and ornamental Design for a Savings Bank, of which the following is a specification, reference being had to the accompanying drawing, forming a part thereof.

Figure 1 is a front elevation of my bank;

Figure 2 is a top plan view;

Figure 3 is a bottom view; and

Figure 4 is a side elevation thereof.

I claim:

The ornamental design for a savings bank, as shown.

ANDREW QUACKENBUSH.
